CLAIM

We claim the ornamental design for shackle related portion of a lock, as shown and described.

DESCRIPTION

FIG. 1 is a perspective view of a first embodiment of a shackle related portion of a lock showing our new design;
FIG. 2 is a front elevation view thereof, the back elevation being a mirror image;

FIG. 3 is a top plan view thereof;

FIG. 4 is a bottom plan view thereof;

FIG. 5 is a right side elevation view thereof;

FIG. 6 is a left side elevation view thereof;

FIG. 7 is a perspective view of a second embodiment of a shackle related portion of a lock showing our new design;
FIG. 8 is a front elevation view thereof, the back elevation being a mirror image;

FIG. 9 is a top plan view thereof;

FIG. 10 is a bottom plan view thereof;

FIG. 11 is a right side elevation view thereof; and,

FIG. 12 is a left side elevation view thereof.

The broken lines shown represent unclaimed subject matter and form no part of the claim.
